Attorney.

UNITED STATES PATENT OFFICE.

MARTIN FURLONG, OF SEATTLE, WASHINGTON.

MINE SAFETY APPARATUS.

1,327,596.

Specification of Letters Patent.

Patented Jan. 6, 1920.

Application filed August 7, 1919. Serial No. 315,953.

To all whom it may concern:

Be it known that I, MARTIN FURLONG, a citizen of the United States, residing at Seattle, in the county of King and State of Washington, have invented certain new and useful Improvements in Mine Safety Apparatus, of which the following is a specification.

This invention relates to improvements in safety appliances for mines.

One of the principal objects of the invention is to provide means by which miners who by accident are confined in a mine, may be instantly located and communicated with by operators on the surface and said miners may be provided with food, air, water and other necessities.

Other objects will appear as the invention is more fully described and explained.

20 In the accompanying drawings:—

Figure 1 is a diagrammatic illustration of a mine equipped with my invention.

Fig. 2 is an enlarged detail view of the end of the pipes.

25 Fig. 3 is a view of the main and auxiliary pipes.

Fig. 4 is an enlarged detail end view of the pipe.

Referring to the drawings, numeral 1

30 indicates the roof of a mine shaft, 2 indicating the horizontal portion or first level of the shaft. 3 indicates staging or framework between the upper level 2, and the lower level 3^a, of the shaft. 4 indicates 35 apertures through the mine levels, by means of which communication between the two levels is afforded. Extending from the level 3^a, through the apertures 4 and the roof, is a main pipe 5, leading to a tool house 6.

40 Within the main pipe 5, are numerous auxiliary pipes 7, three being shown merely to illustrate the application of the invention, it being understood however, that a larger number of pipes may be used if desired.

45 Extending from the main pipe 5 and within the level, is a branch 8, and also extending through the branch 8, are sub-branches 7^a leading from the auxiliary pipes 7. Each of the sub-branches 7^a in the level 2, and the

50 ends of the auxiliary pipes 7 in the level 3^a is closed by a cap 9. Each cap 9 is normally held closed by a spring 9^a. Extending through one of the auxiliary pipes may be an electrical circuit 9^b, which is normally 55 open, but when closed energizes a magnet 9^c to open one of the caps 9. There would

of course be a separate circuit for each cap, so that when those upon the surface are informed of the level in which the miners are confined the corresponding cap can be 60 readily opened by closing the proper circuit by means of a push button or switch.

Extending from each level 2 and 3^a is signal circuit 15, leading to a bell in the tool house, and controlled by means indicated at 16.

In operation, if an explosion occurs in a level, and the operators from the surface are unable to reach the mine or cannot communicate with the entombed miners, the latter pushes the button and signals the tool house of the trouble, which indicates that a disaster has occurred. Of course a telephone may be included in the signal circuit.

The entombed miner may operate one of 75 the closures, and by signals he may be supplied with air, water, or liquid food. If however the miner should be overcome by the gas, and is therefore not physically able to open one of the closures, the operator in 80 the tool house pushes the necessary button, and the magnet acts to withdraw the spring lock, and air, or other essentials to life can be introduced to the level. By operating the various buttons, air, water and food 85 can be supplied, until assistance can be rendered through the main shaft.

Obviously if a miner in one of the levels be physically unable to do more than press a signal button, it would indicate that the 90 first necessity would be fresh air, and this could be immediately furnished by suitable air pumps, located in the tool house 6. If the explosion has been so severe, not only to cause deathly gas but also cause the earth 95 to cave in, completely entombing the occupants of the level, it would not be necessary to delay furnishing occupants of the floor all the necessities of life until proper excavation could be made; it only being necessary to furnish these necessities in the order 100 of their importance, first air, next water could be pumped through one of the auxiliary pipes, and finally forced through still another pipe so on, until the final rescue of 105 the entombed miners had been accomplished.

The parts are so arranged that any particular level of a mine can be supplied with the necessities of life, without opening the closures in the other levels. This provision 110 avoids waste, and insures the necessities being delivered where they are most needed.

If perchance more air, water or food is furnished from the tool house, than is required, the miner may manually cut off the supply by actuating the respective closures.

5. What I claim is:—

1. In a safety system for mines, the combination of a main pipe extending from above the surface into a mine, a plurality of auxiliary pipes contained within the main pipe having openings upon each floor of the mine, means for normally closing the auxiliary pipes, and means operable from the surface for controlling the said closing means.

2. In means for supplying entombed miners with the necessities of life, the combination of a plurality of pipes extending from a point above the surface to the various levels in the mine, a closure for each pipe, a latch for each closure, means above the surface for operating each closure, said latches also being manually operable to be under the control of the entombed miners, and signals extending from the levels of the mines to and above the surface thereof. 15 20 25

In testimony whereof I affix my signature.

MARTIN FURLONG.
